J. E. WHITFIELD

BRACE

Filed Dec. 30, 1924

UNITED STATES PATENT OFFICE.

JOSEPH E. WHITFIELD, OF EAST PITTSBURGH, PENNSYLVANIA.

BRACE.

Application filed December 30, 1924. Serial No. 758,837.

To all whom it may concern:

Be it known that I, JOSEPH E. WHITFIELD, a citizen of the United States, residing at East Pittsburgh, in the county of Allegheny and State of Pennsylvania, have invented 5 certain new and useful Improvements in a Brace, of which the following is a specification.

The present invention relates to braces 10 for the reception and operation of bits, drills and the like and has for its prime object to provide means adapted for use in a ratchet brace for preventing rotation of the tool in the brace in the wrong direction. 15 In using the ordinary ratchet brace, the friction of the engaging pawl is often sufficient to rotate the tool in the opposite direction to that desired during the oscillation of the brace. This is true especially in the beginning 20 of a drilling operation. With the present attachment, this undesirable back rotation is eliminated.

Another important object of the invention is to provide an attachment of the 25 nature specified which may be placed in an out of the way position when not in use.

Another important object of the invention is to provide an attachment of this nature which is operable by the ratchet operating 30 means already found on the conventional ratchet brace.

A still further very important object of the invention is to provide a device of this nature having an extremely simple and efficient 35 structure, one which is reliable in operation, inexpensive to manufacture, compact, strong, durable, not liable to readily get out of order, handy, easy to manipulate, and otherwise well adapted to the purpose 40 for which it is designed.

With the above and numerous objects in view as will appear as the description proceeds, the invention resides in certain novel features of construction, and in the combination and arrangement of parts as will be hereinafter more fully described and claimed.

In the drawing:

Figure 1 is an elevation of the brace embodying the features of my invention, the upper or handle portion thereof being shown in section.

Figure 2 is a detail vertical section taken through the ratchet mechanism of the improved brace.

Figure 3 is a transverse section taken sub-

stantially on the line 3—3 of Figure 1 looking in the direction of the arrow.

Figure 4 is a detail section taken substantially on the line 4—4 of Figure 3, and 60

Figure 5 is a detail section taken substantially on the line 5—5 of Figure 1 looking in the direction of the arrow.

Referring to the drawing in detail it will be seen that the brace which has been disclosed is formed similar to the conventional type of ratchet brace now commonly in use, and includes among other improved elements the following conventional elements, namely, the handle portion 5 having on 70 its upper end the grip 6, the crank 7 provided with the intermediately disposed grip 8, and the chuck or tool engaging portion 9. Of these conventional elements I shall only describe in detail as far as they are pertinent to my improvements. 75

The chuck 9 includes the usual shank 10 reduced at 11 and journaled through the spaced extremities 12 of the lower arm of the crank 7. The upper end of the reduced 80 portion 11 of the shank 10 is spaced from the upper extremity 12 and is in the form of a ratchet head 13. A second ratchet member 14 is mounted to slide on and rotate with the upper portion of the reduced shank, 85 the ratchet teeth being formed on the edge thereof and pitched oppositely to the ratchet teeth on the head 13. A spring 15 normally holds the ratchet member 14 in a down position, that is in engagement with the upper 90 extremity 12 of the lower arm of the crank.

As is conventional in ratchet braces the lower arm adjacent its extremity is provided with an annular groove 16 having humps 17 and 18 at spaced intervals for alternately 95 engaging the two pawls 19 pivoted in longitudinal grooves 20 in the crank arm and normally held out of engagement with the ratchet wheel 21 keyed on the reduced portion 11 between the extremities 12. By rotation of the collar 22 the humps 17 and 18 carried thereby will force alternately the pawls 19 in engagement with the ratchet wheel 21. 100

In my improved structure I provide a 105 pair of spaced longitudinally extending grooves 24 in the lower arm of the crank 7, the bottoms of which are curved to form humps 25 which provide fulcrums for bars 26, one end of which terminates within the collar or sleeve 22 to be engaged by humps 110 27 formed interiorly thereof which cause

the bars to swing so that their outer ends disposed below the ratchet member 14 will lift this member 14 so that its ratchet teeth extend above the ratchet teeth of the member 13. The humps 26 are located so as to be in engaging position with respect to the bars 26 only when one of the humps 17 or 18 is engaged with its respective pawl 19. This arrangement is determined by the pitch 10 of the teeth on the members 13 and 14 as will be readily understood by those skilled in the art.

The handle member 5 in the present embodiment of the invention is formed hollow and at the lower or inner end thereof there is mounted a hollow keeper 28 having therein an annular groove 29, the lower wall of which is provided with diametrically opposed notches 30 for a purpose which will 20 be brought out later.

A hollow member 31 has a head 32 on its upper end slidable within the handle portion 5 and a second hollow member 34 has a head on its upper end as at 36 slidable 25 in the hollow member 31 and at its lower end is provided with a transversely extending pin 37 adapted to engage the ratchet teeth of either member 13 or 14. The hollow members 31 and 34 form a supporting 30 telescoping stem for the pin 37 and a spring 38 normally holds this stem in the extended position shown in Figure 1 so that the pin 37 is engaged with the ratchet teeth of the member 13 or 14 which may be actively 35 disposed, depending upon the positioning of bars 26.

It is preferable to provide a pocket 40 in the upper end of the reduced portion 11 for the reception of the lower end of the 40 member 34 of the telescopically constructed stem in order to hold it in proper alignment. The members 31, 34, and pin 37 and the ratchet member 13 or 14 with which it is engaged will afford sufficient friction to 45 overcome the tendency of the back rotation of the chuck 9 and the tool therein during the operation of the ratchet wrench.

It is thought that a clear understanding 50 of the construction of the present embodiment of the invention will be understood with its advantages without a more detailed description. It should be apparent from the above that I have provided a device 55 which will effectively overcome the undesirable back rotation of the tool during the operation of a ratchet wrench and that the attachment is capable of being moved to an out of the way position by telescoping the members 34 and 35 in the hollow handle 60 portion 5, passing the pins 37 through the notches 30 and rotating it into engagement with the annular groove 29, this operation being similar to the bayonet slot arrangement which is quite common. It will 65 further be apparent that the improvements

are of a very simple nature and may be incorporated in a ratchet wrench at a reasonably low cost or manufactured initially therewith and that the improvements are not liable to readily get out of order and 70 do not require any great skill in order that they may be properly manipulated with the other usual features of a ratchet wrench. The present invention has been disclosed in the preferred embodiment thereof, but it 75 is to be understood that the same is susceptible of numerous changes in the details of construction, and in the combination and arrangement of parts without departing from the spirit or scope of the invention as 80 hereinafter claimed or sacrificing any of its advantages.

Having thus described the invention, what I claim is:—

1. In a brace, a hollow handle portion, a 85 crank rotatable thereon, a chuck on the crank, a ratchet mechanism associated between the crank and the chuck, a ratchet member on the upper end of the shank of the chuck and having teeth disposed in one 90 direction, a slideable ratchet member on the shank of the chuck and having teeth disposed oppositely to those on the other ratchet member, means for moving the second ratchet member above the first ratchet 95 member, a spring pressed stem telescopically associated with the hollow handle, a pin at the lower end of the stem for engaging the teeth of one of the ratchet members, and means holding the second ratchet 100 member normally below the first ratchet member.

2. In a brace, a hollow handle portion, a crank rotatable thereon, a chuck on the crank, a ratchet mechanism associated between the crank and the chuck, a ratchet member on the upper end of the shank of the chuck and having teeth disposed in one direction, a slideable ratchet member on the shank of the chuck and having teeth disposed oppositely to those on the other ratchet member, means for moving the second ratchet member above the first ratchet member, a spring pressed stem telescopically associated with the hollow handle, a pin 115 at the lower end of the stem for engaging the teeth of one of the ratchet members, means holding the second ratchet member normally below the first ratchet member, means on the handle for engaging the pin 120 and holding it in an out of the way and inoperative position.

3. In a ratchet brace of the class described, an attachment for preventing back rotation of the tool associated with the 125 brace including a pair of ratchet members rotatable with the tool and having teeth, the teeth of one member being oppositely disposed from those of the other member, a spring pressed pin engageable with the 130

ratchet members, and means for operating the ratchet members of the attachment so that they will be alternately disposed in an operative position in respect to the spring 5 pressed pin to be engaged thereby.

4. In a ratchet brace of the class described, an attachment for preventing back rotation of the tool associated with the brace including a pair of ratchet members rotatable with the tool and having teeth, the teeth of one member being oppositely dis-

posed from those of the other member, a spring pressed pin engageable with the ratchet members, means for operating the ratchet members of the attachment so that they will be alternately disposed in an operative position in respect to the spring 15 pressed pin to be engaged thereby, and means for holding the pin in an out of the way position.

In testimony whereof I affix my signature.

JOSEPH E. WHITFIELD.
